UNITED STATES PATENT OFFICE.

SAMUEL PRESCOTT BUSH, OF COLUMBUS, OHIO, ASSIGNOR TO THE BUCKEYE STEEL CASTINGS COMPANY, OF COLUMBUS, OHIO.

CAR-COUPLING DEVICE.

Application filed July 8, 1924. Serial No. 724,833.

This invention relates to car coupling devices and particularly to means for connecting an automatic coupler with a hook coupler.

5 In accordance with the present invention, the coupling means between the automatic and hook couplers includes two connected shackles, one of which is freely connected with the automatic coupler and the other 10 of which is freely connected with the hook coupler, said shackles being connected together through the medium of a trunnion block provided with two pairs of trunnions disposed at right angles to each other, one 15 of said shackles having pivotal connection with one pair of trunnions and the other shackle having pivotal connection with the other pair of trunnions of the trunnion block.

20 In the accompanying drawings:—

Figure 1 is a plan view illustrating the invention.

Figure 2 is a side view, and

25 Figure 3 is a view showing the positions which the shackles may assume when the hook coupler approaches the automatic coupler.

A portion of a car end structure is shown at 1 and through the same, the draw bar 30 or shank of an automatic coupler head passes,—the latter being of that type which employs a knuckle 3 pivotally connected with the head by a pivoted pin 4, and a guard arm 5 at the opposite side of the 35 head.

Within the mouth 6 of the automatic coupler a pulling block 7 is located for the accommodation of means for connecting the automatic coupler with a hook coupler, the 40 latter being represented at 8.

In the present instance, the pulling block is shown as being formed at one end with a tongue 9 which enters the intermediate recess 10 in the free end portion of the pivoted knuckle 3. Adjacent to said tongue, the pulling block is provided with an enlargement 11 forming shoulders which are made to conform to the contour of and bear against the rear face of the pivoted knuckle. 45

50 At its other end the pulling block is formed with an extension 12 which enters a recess or socket 13 in the guard arm of the automatic coupler head. The rear face of the intermediate portion of the pulling block is 55 curved or depressed so as to form a seat

14 to receive a member of the connecting means so that said member will, when in use, be disposed between the free end of the pivoted knuckle and the guard arm and in order to prevent accidental escape and loss of the pulling block from said connecting member, said block is provided with a flange 15 located between said member and the guard arm. The pulling block may be connected by means of a chain 16 with the 60 pivot pin of the pivoted knuckle.

The connecting means between the pulling block and the hook coupler comprises two shackles 17 and 18, the latter being adapted for attachment to the hook coupler 70 and the former caused to embrace the pulling block and be guided to and disposed so as to normally engage the seat 14 in said block. The shackles 17 and 18 are connected together through the medium of a 75 trunnion block 19. A bolt passes transversely through the trunnion block 19 and projects at both ends beyond the same so as to provide trunnions 20—20 which receive the arms of the shackle 17 and provide 80 pivotal connection for the same which will permit vertical movements of the connected ends of the shackle. The trunnion block is provided with trunnions 21 disposed at right angles to the trunnions 20—20 and to 85 said trunnions 21 the end portions of the arms of the shackle 18 are pivotally connected whereby the connecting shackles may have horizontal play. It is evident that instead of employing a bolt to provide the 90 trunnions 20, the latter may be formed rigid with the block as are the trunnions 21.

The connecting devices between the automatic and hook couplers and comprising shackles connected together through the 95 medium of a trunnion block, will operate freely and when the hook coupler approaches the automatic coupler, said connected shackles will readily assume the positions shown in Figure 3 without danger 100 of binding or cramping.

When the connecting devices including the shackles and the pulling block are not in use, they may be suspended from a hook 22 secured to the car end structure 1, as 105 illustrated in Figure 2.

Having fully described my invention what I claim as new and desire to secure by Letters-Patent, is:—

The combination with an automatic cou-

pler including a guard arm and a pivoted knuckle, of a pulling block having a part to enter the guard arm and a part to engage the pivoted knuckle, a shackle having its bight engaged around said block, a trunnion block disposed between the ends of the shackle, trunnions on opposite sides of the trunnion block engaged in the ends of the shackle, other trunnions on said trunnion block at right angles to the first-named trunnions, and a second shackle having its ends directly engaging said second-named trunnions and its bight arranged to be engaged over a hook coupler.

In testimony whereof, I have signed this 15 specification.

SAMUEL PRESCOTT BUSH.
